(57) **CLAIM**

The ornamental design for a fan grill, as shown and described.

DESCRIPTION

FIG. 1 is a perspective view of a fan grill showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a partial enlarged view of the fan grill, taken from circle 8 of FIG. 1.

The broken lines shown in the drawings are included for the purpose of illustrating portions of the fan grill that form no part of the claimed design.
